UNITED STATES PATENT OFFICE.

WILLIAM L. KELLOGG, OF DETROIT, MICHIGAN.

TANK-CAR CONSTRUCTION.

1,290,575.

Specification of Letters Patent.

Patented Jan. 7, 1919.

Application filed August 20, 1917. Serial No. 187,132.

To all whom it may concern:

Be it known that I, WILLIAM L. KELLOGG, a citizen of the United States, residing at Detroit, in the county of Wayne and State 5 of Michigan, have invented a certain new and useful Improvement in Tank-Car Constructions, of which the following is a full, clear, concise, and exact description, reference being had to the accompanying drawings, forming a part of this specification.

10 This invention relates to improvements in tank car constructions.

As is well known, in the operation of tank cars, the tanks are frequently subject to wide 15 variations of thermal conditions due to the pouring of hot oil or other commodities within the tank and the cleaning of the tanks by steam. Heretofore, considerable difficulty has been experienced in the building 20 and operation of tank cars in securing proper anchorage between the tank and the car underframe which would permit of the expansion incident to the thermal changes above referred to. So far as I am aware, 25 the general method heretofore employed to permit the expansion of the tank has been by the use of a so-called center or "one-point anchor" located in the center of the tank, the halves on either side thereof being unsecured 30 to the underframe except by tank straps or bands.

While the foregoing construction permits of the expansion of the tank, it is obvious that the bands are the only means availed of 35 to hold the end portions of the tank down and to prevent them from swaying laterally with respect to the underframe. Repeated expansion and contraction of the bands and the constant strains imposed thereon, soon 40 tend to loosen the bands with the result that too great freedom of movement is permitted the end portions of the tank both vertically and laterally, and enormous strains due to the twisting or swaying of the tank 45 relatively to the underframe, are imposed both upon the one-point anchor and the plates of the tank itself with frequent damage to the tank resulting in the rupturing of the seams.

50 One subject of my invention is to provide an arrangement for anchoring tanks to underframes near the ends of the tank and so arranged as to positively prevent any undue relative movement between the tank 55 and the underframe, either vertically or laterally but at the same time providing the

necessary means for freely accommodating the expansion of the tank under thermal changes and without danger of rupturing the tank seams.

60

Another object of my invention is to provide tank anchors located in the body bolster of the car and so employed in combination with the tank saddles as to eliminate the necessity for the tension member of the body 65 bolsters now usually employed.

The invention furthermore consists in the improvements in the parts and devices and in the novel combinations of the parts and devices herein shown, described and made 70 the subject matter of claims.

In the drawings forming part of this specification, Figure 1 is a transverse, vertical sectional view of a portion of a tank car adjacent the body bolster and showing 75 my improvements in connection therewith. Fig. 2 is a vertical, longitudinal, sectional view, parts being broken away in order to prevent crowding the drawing, the section being taken substantially on the line 2—2 of 80 Fig. 1, and illustrating the tank anchors at both ends of the car. Fig. 3 is a detail, transverse, sectional view, taken substantially on the line 3—3 of Fig. 2. And Fig. 4 is a perspective view of one of the dovetail keys 85 employed with my improvement.

In said drawing, 10 denotes the tank of a tank car, the lower portion only of the tank being shown in the drawings. The center sill of the underframe is formed by two outwardly turned channels 11—11 in the usual manner, the latter having a cover plate 12 secured at their tops to thereby form a column. Near each end of the tank, the channels 11 are secured to a body bolster member 13, the latter having a center bearing plate 14 which co-operates with a corresponding center bearing plate 15 carried by the truck bolster 16. The truck bolster 16 and body bolster member 13 are provided 90 with any suitable side bearings, such as those illustrated at 17—17.

95 In carrying out my invention, the tank is anchored to the underframe near each end thereof and at the body bolsters. At one end, 100 the left hand end as viewed in Fig. 2, the anchor is formed by a tank anchor plate 18, an underframe anchor plate 19 and a double dovetail key 20. The tank is anchored at the opposite end by a similar means, with slight 110 modification, as hereinafter pointed out, the tank anchor plate being designated 118 and

the underframe anchor plate 119, the double dovetail key being shown at 120. Each of the tank anchor plates 18 and 118 is provided with a curved seat 21 on its upper face fitting the under side of the tank, and the laterally extended flange portions 22—22 of each of said plates 18 and 188 is riveted to the tank, as indicated at 23—23. Each of the underframe anchor plates 19 and 119 has laterally extending horizontal flanges 24—24 which are adapted to be riveted to the upper flanges of the channels 11—11, as by the rivets 25—25.

Each set of anchor plates 18 and 19 and 118 and 119 is provided with opposed dovetail grooves 26 and 27 extending the entire length of the anchor plates and when the parts are properly positioned, said dovetail grooves 26 and 27 are adapted to receive a nicely fitting double dovetail key 20 or 120. Each of said keys 20 and 120, as clearly shown in Fig. 4, is undercut along its sides, as indicated at 28—28 so that when the keys are slipped into position, the sets of anchor plates are securely locked against either relative vertical or lateral movement. The keys 20 and 120 are somewhat longer than the anchor plates and each key is perforated at its ends, as indicated at 29, to receive a retaining pin 30, the pins 30 being held by cotters 31 to thereby prevent accidental displacement of the dovetail keys.

At one end of the car, the coöperating anchor plates are preferably formed so as to prevent any relative longitudinal movement therebetween, and to accomplish this result, the tank anchor plate 18 is provided with a series of transversely extending grooves or recesses 32—32 in which snugly fit a corresponding series of transversely extending lugs or ribs 33—33 formed on the upper face of the underframe anchor 19. The foregoing described series of coöperating recesses and lugs 32 and 33 will obviously prevent relative longitudinal movement between the anchor plates. At the opposite end of the car, the tank anchor plate 118 is also provided with a series of transversely extending recesses 132—132 and the underframe anchor plate 119 with corresponding transversely extending lugs or ribs 133—133, but in this instance, the recesses are made sufficiently wider than the lugs 133 to accommodate the maximum expansion of the tank. In applying the anchor plates 118 and 119, they will be positioned as shown in Fig. 2, that is, with the spacing 34 between the interfitting parts of the anchor plates nearest the anchor plates at the other end of the car.

With this construction, it is apparent that at one end of the car, the left hand end as viewed in Fig. 2, a rigid but detachable connection is provided between the tank and the underframe which positively prevents rela-

tive movement between the tank and the underframe either vertically, laterally or longitudinally. At the opposite end of the car, the anchoring means will positively prevent either vertical or lateral relative movement between the tank and the underframe but will accommodate relative longitudinal movement between the anchor plates, and this is permitted because of the formation and disposition of the double dovetail key 120. With this arrangement, it is obvious that the expansion and contraction of the tank takes place substantially entirely at one side of the anchor at the left hand end of the car as viewed in Fig. 2, and due to the type of anchoring means employed, tank bands may or may not be used as the manufacturer determines.

At each body bolster, I employ a pair of saddle castings 35—35, each of which is of substantially triangular formation having a curved upper surface 36, vertical outside leg 37 and inclined inner leg 38. Each of the saddle castings 35 is bolted or otherwise rigidly secured to the outer end of the body bolster member 13, as indicated at 39—39. At their inner ends, the castings 37 are provided with horizontally extending flanges 40 which overlap extended portions 41—41 of the underframe anchor plates 19 and 119 and are securely riveted thereto, as indicated at 42. Suitable blocks of wood 43—43 are interposed between the saddle castings and the tank, the blocks of wood being held in position by the bolts 44—44. Each of the saddle castings 35 is preferably provided on its outer side with a laterally extended bracket 45 by which the running-boards 46 are supported and, if desired, each of the saddle castings may also be provided with integrally formed push-pole brackets 47 and 48.

With the bolster construction above described, it is apparent that I eliminate the usual arch bar or tension member employed in the ordinary body bolster of a tank car, thus effecting a saving in the cost of material without in any way weakening the construction.

Although I have herein shown and described what I now consider the preferred manner of carrying out my invention, the same is merely illustrative, and I contemplate all changes and modifications that come within the scope of the claims appended hereto.

I claim:

1. In a tank car, the combination with an underframe and a tank; of means for securing the tank to the underframe near both ends of the tank, said means preventing vertical and lateral movement of the tank with respect to the underframe but permitting movement of the tank lengthwise of the underframe due to the expansion and contraction of the tank, the means at each end

of the tank including, a tank anchor plate, an underframe anchor plate, and a dovetail connection between the anchor plates.

2. In a tank car, the combination with an 5 underframe and a tank; of means for securing the tank to the underframe near both ends of the tank, said means preventing vertical and lateral movement of the tank with respect to the underframe but permitting 10 movement of the tank lengthwise of the underframe due to the expansion and contraction of the tank, the means at each end of the tank including, a tank anchor plate, an underframe anchor plate, and a dovetail 15 connection between the anchor plates, the anchor plates at one end of the car being relatively longitudinally movable and the anchor plates at the opposite end of the car being relatively immovable longitudinally. 20 3. In a tank car construction, the combination with the tank and the underframe; of tank anchor plates secured to the tank near each end thereof; underframe anchor plates secured to the underframe opposite 25 the tank anchor plates; and a double dovetail key interposed between and detachably connecting each set of tank and underframe anchor plates. 30 4. In tank car construction, the combination with the tank and the underframe; of tank anchor plates secured to the tank near each end thereof; underframe anchor plates secured to the underframe opposite the tank anchor plates; and a double dovetail key 35 interposed between and detachably connecting each set of tank and underframe anchor plates, said keys being extended lengthwise of the car; one set of said anchor plates having integral means preventing relative longitudinal 40 movement therebetween.
5. In a tank car construction, the combination with the center sills of the car underframe and the tank; of means for securing the tank to the center sills near each end of the tank; and a body bolster construction 45 near each end of the car, each of the said body bolster constructions including, a lower body bolster compression member having its ends extending outwardly beyond the center sills on each side thereof, and a pair of saddle castings, one on each side of the center sills, each saddle casting being of generally triangular formation with a vertically extending outside leg and a downwardly and outwardly inclined leg, the saddle casting 50 having its lower corner secured to the compression member near the adjacent end of the latter, the inner corner of the casting being secured adjacent the center sills. 55
6. In a tank car, the combination with an 60 underframe and a tank, of means for securing the tank to the underframe near both ends of the tank, each of said means including a tank anchor plate, an underframe anchor plate and a removable key, each set of 65 anchor plates having shouldered engagement, the set of anchor plates at one end of the car being relatively longitudinally movable and the other set of anchor plates at the opposite end of the car being relatively 70 immovable longitudinally, both sets of anchor plates being separable in a vertical direction upon removal of said keys whereby the tank may be lifted from the underframe, vertically, when said keys are removed. 75

In witness that I claim the foregoing I have hereunto subscribed my name this 3d day of August, 1917.

W. L. KELLOGG.
